UNITED STATES PATENT OFFICE.

JOSEPH F. WILSON, OF LAWRENCE, MASSACHUSETTS.

FIRE-STOP CONTROL.

1,334,925.

Specification of Letters Patent. Patented Mar. 23, 1920.

Application filed August 13, 1917. Serial No. 186,073.

To all whom it may concern:

Be it known that I, JOSEPH F. WILSON, a citizen of the United States, residing at Lawrence, in the county of Essex and State 5 of Massachusetts, have invented new and useful Improvements in Fire-Stop Control, of which the following is a specification.

The present invention has reference to fire stop curtains adapted for use in theaters and other places of public gathering to prevent flames originating on the stage from passing into the auditorium. It is the object of the invention to provide a releasing means in connection with a fireproof drop 10 curtain or other fire stop adapted to be operated either automatically or by human agency upon the occurrence of a fire to permit the curtain or fire stop to drop and thereby separate the apartment in which the 15 fire has originated from the apartment in which people are gathered. The invention is useful not only in connection with the drop curtain of a theater stage, but also to control fire shutters such as are provided in theaters above the stage to be opened for 20 release of flames and smoke when a fire occurs on the stage, and in general for any use in which it is desired to separate one apartment from another quickly or to open 25 a relief outlet of any sort.

The invention is applied to devices in the nature of fire stops, shutters, curtains, etc., which are held in one position by a cable and are adapted to be automatically brought 30 into another position either by their own weight or by a counter-weight when the cable is released. Accordingly this invention includes a holder for such cable and means for releasing such holder when the 35 contemplated emergency occurs. The invention also constitutes in part a distant controlling means for effecting release of such cable holder in the circumstances indicated, which distant controller may be operated manually by a person on the spot 40 or automatically by the heat developed by a fire.

In the drawings forming part of this application I have shown two of the possible 45 embodiments of the invention.

Figure 1 is an elevation representing part of a cable with a clamp for the same and locking and releasing means for the clamp in elevation, all contained in a case which 50 is represented in section, and shows also

diagrammatically an electric circuit for operating said releasing means and the controllers in said circuit.

Fig. 2 is a cross sectional view of a detail of the clamp shown in Fig. 1, taken on line 2—2 of Fig. 1.

Fig. 3 is a view similar in general to Fig. 1 illustrating a modification of the invention.

Referring to the drawings, 4 represents a 65 cable which may be considered as the cable leading to the hoist of a theater drop curtain, and it may also be considered as typical of any movable means for holding such a safety contrivance as a theater drop curtain in the raised position or a fire shutter in the closed position, such curtain, shutter or the like being so poised or counter-weighted as to tend to assume the safety position when the cable is allowed to move. 70 From now on I will assume that the invention is applied in connection with a theater drop curtain which is raised when open and adapted to be lowered by gravity so as to close the stage opening, making this assumption for convenience and brevity of the description and without intending thereby to indicate limitation of the invention to any particular combination or particular use 75 otherwise than as limitation is expressly required by the terms of the claims. 80

The means for holding the cable against endwise movement and thereby retaining the curtain in the raised position comprises two clamping jaws 5 and 6 which are arranged on opposite sides of the cable and are adapted to grip the same between them. These jaws are preferably blocks of wood having rounded grooves in those sides or edges which bear against the cable, and they 90 are so mounted as to be movable toward and away from the cable, each having slots 7 and 8 through which project supporting studs 9 and 10 respectively. Such studs are mounted on the wall of the case 11 indicated in section in Figs. 1 and 3; or they may be mounted on a wall of the building 95 or any other convenient support. 100

In the embodiments of the invention here shown each of the jaws is independently 105 movable to grip and release the cable, the jaw 5 being thus operable manually by means of a pivoted hand lever 12 having a cam portion 13 which bears against the outer side of the jaw, and the other jaw 6 110

being thus operated by a lock which may be released by automatic mechanism through an indirect control. Two forms of the latter locking or holding means are illustrated, that shown in Fig. 1 being the preferred form which I will now describe.

The part which directly holds the jaw 6 in clamping position is a lever 14 pivoted on a stud 15 and having a short arm 16 provided with a roll 17 which bears against the outer side of the jaw adjacent to an inclined surface 18 on such outer side. The longer arm of lever 14 carries by means of a pivot 19 relatively remote from the fulcrum stud 15 a secondary lever 20, the arms of which are of unequal length. The short arm 21 of this secondary lever rests on an abutment 22 which is mounted on a holder 23 fixed to the wall of the case 11 or other support 10 while the long arm of its lever rests on a toe 24 projecting from a dog 25 which is pivoted on a fixed fulcrum pin 26. A trip arm 27 stands in the path of movement of the dog and thus sustains the latter in the position 15 shown in Fig. 1 so that it cannot be displaced by the pressure applied to its toe 24; but the line in which pressure is applied to the toe by lever 20 is at one side of fulcrum 26, wherefore such pressure tends to displace 20 the dog, and normally causes the long arm of the dog to bear on the trip.

Trip arm 27 is part of the lever 28 pivoted on a fixed fulcrum 29 and carrying the armature 30 of an electromagnet 31. A spring 32 holds the trip arm in the position shown in the drawing, in which position the lever arm 28 bears against a stop 33 and the armature 30 is near enough to the pole piece 34 of the electromagnet to be strongly attracted thereby when the magnet is energized.

The winding of the electromagnet is connected to two conductors 35 and 36, which form part of an electric circuit containing 45 a battery 37 or other source of energy and in which there is a switch 38 and a controller 39. Switch 38 may be considered as a push button or any other sort of switch and as typifying one or a number of controllers 50 adapted to be operated by human agency at one or more points distant from the lock. Thus, for example, in a theater I may provide switches, in parallel circuits including the magnet and battery, and located in the 55 stage manager's station, the chief usher's station, the box office, stations of watchmen, and elsewhere, or in any one or more of the designated locations. 39 typifies an automatic circuit controller which is contained 60 in circuit with the magnet and battery as shown, and may be connected with an automatic fire alarm so as to be operated by or simultaneously with the same, or it may be connected with an automatic sprinkler system or sprinkler alarm, so as to close the

circuit and release the lock when heat is developed by a fire sufficient to put the automatic sprinklers or the alarm in operation.

When the magnet circuit is closed by either of the means indicated, the armature 70 30 is attracted and the trip arm removed from the path of that part of the dog 25 which it obstructs. This leaves the dog free to move so that its toe no longer provides a rigid support for the lever 20. It should 75 be noted that the arm 16 of lever 14 is at such an inclination that the line in which the pressure of the compressed cable acts through the jaws 6 on the roll 17 is inclined to the arm 16 and extends at one side of the 80 fulcrum 15, whereby it causes pressure to be exerted by the lever arm 21 against the abutment 22, which causes the long arm of this lever to press against the toe 24. Therefore when the dog 25 is released as above described 85 the roll 17 is no longer held rigidly against the jaw, but is free to be displaced leaving the jaw loose and releasing the cable. The arm 21 then falls below the abutment 22.

In order to secure the clamp again it is only necessary to raise the lever 14 until the arm 21 passes above the abutment 22. The latter is mounted to slide in a socket 40 in its holder and is pressed outward by a spring 41, and it has a beveled face at the side opposite to that on which the arm 21 rests. Thus when the lever is restored to the locking position the arm 21 wipes across said beveled face, retracting the abutment until 100 the arm has passed it, when the abutment is shot forward by its spring. The arm 21 then strikes a fixed stop 42, whereby further movement of lever 14 in the same direction causes the long arm of lever 20 to strike a 105 finger 43 on the dog and restore such dog to the locking position. In being so restored the end of the dog passes across the trip arm 27 and displaces the latter, which is then brought into the locking position by the 110 spring 32. Preferably trip arm 29 is connected by a pivot 44 with the lever 28, which permits displacement of the trip arm in the direction last indicated without displacing the lever, but such trip arm has a finger 45 115 extending beside an adjacent part of the lever in such a manner that it causes the movement of the lever when attracted by the magnet to displace the trip arm positively.

In order to increase the security of the 120 grip of the clamps on the cable, I provide metal inserts 46, of which one or more are set into the edges of the clamps next to the cable so as to cross the grooves in such edges wherein the cable lies. These inserts project 125 somewhat from the cable receiving grooves so that they are adapted to bite into the cable, as shown in detail in Fig. 2, when the jaws are closed.

Preferably the clamping jaws, automati- 130

cally operated lock, and the automatic controlling means, are inclosed in the case 11 to avoid injury and prevent tampering with them. The cable passes through openings 5 in the case and so does the handle part of the manually operated lever 12. The latter is the device which is ordinarily and regularly used for securing the curtain when it is raised and lowered in the course of the 10 atrical performances. The automatic release is an emergency contrivance exclusively. After being set ready for use the case is closed, and it is then ordinarily never opened except to reset the release device 15 following an emergency when either the automatic controller or a manually operated distant switch has been worked for the purpose and with the effect already described.

An important feature of the automatic 20 controlling mechanism is that it is free of close fitting and sliding parts, and is, therefore, not liable to get out of order. It will be observed that the secondary lever 20 which supports the securing lever does not 25 slide upon either of its abutments, but rocks on the same, wherefore it is not liable to become fastened thereto by accumulation of dust, rust, etc., from long disuse. The only part which slides upon another part 30 is the trip arm 27, which has a short sliding movement on the long arm of the dog, but the pressure exerted on the trip by this arm is so very light that the friction resisting displacement of the trip is inappreciable. 35 The dog 25 is the last of a train of three levers, each of which is a power diminishing lever.

In the modification shown in Fig. 3, the 40 only substantial difference is found in the stop lever release or trip. The stop lever 14 is essentially the same as that already described, except that it lacks the secondary or bridge lever 20 and bears at the outer end of its long arm directly on the toe 24^a 45 of a dog 25^a. The latter has a long arm which bears against a stop dog 47 pivoted on a fulcrum pin 48 and having a weighted arm 49 which tends to displace its stop abutment out of the way of the supporting dog 50 25^a. The stop abutment and the weighted arm are held in the position shown in the drawing by a latch arm 27^a on an armature 55 lever 28^a interposed in the path of an arm 50 on the stop dog. All other elements shown in Fig. 3 are the same as those shown in Fig. 1 and are designated by the same reference numbers.

In order to distinguish the two dogs shown in Fig. 3 from each other, I have 60 called the one which directly engages the locking lever 14 and supports the same the "supporting dog" and the other the "stop dog".

This curtain release device is adapted to 65 be used and operated simultaneously with

the emergency exit doors described in my pending application Serial Number 186,072, filed August 13, 1917, and to be controlled by the same distant controlling means; this fire stop or fire release shutter forming 70 jointly with the automatically controlled exit doors a comprehensive safety means for theaters and the like adapted to prevent as far as possible the entrance of flames to an auditorium and at the same time incidentally 75 permit egress of the audience.

Preferably the hand lever 12 is adjustable, its pivot 12^a being mounted adjustably in a slot 12^b in the casing, or the opposite ends of the pivot may be in slots in opposite 80 sides of the casing.

What I claim and desire to secure by Letters Patent is:—

1. A fire stop control apparatus comprising a cable, complemental clamps embracing 85 and gripping said cable, each of said clamps being movable away from the cable independently of the other, a casing containing said clamps, an abutment for one of said clamps having a handle projecting out of 90 the casing and operable manually to release the clamp with which it is engaged, a displaceable abutment for the other of said clamps normally holding the latter in engagement with the cable, automatic means 95 for releasing the latter abutment, said automatic means and the abutment being contained within the case, and a distant control for causing operation of said automatic means for the purpose stated. 100

2. A fire stop control apparatus comprising a cable, complemental clamps embracing said cable and adapted to grip the same between them, separate abutments for the several clamps each arranged to hold the clamp 105 with which it co-acts in engagement with the cable and each being displaceable to permit release of such clamp, manual means for making one of said abutments inoperative and automatic means for making inoperative the other of said abutments. 110

3. The combination with a fire stop control cable of complemental clamps embracing said cable and adapted to grip the same between them, a releasable abutment bearing 115 against one of said clamps for holding the same against the cable and having a handle whereby it may be manually displaced to release said clamp, a second displaceable abutment bearing against the 120 other of said clamps to hold the same against the cable, an electromagnet, tripping mechanism controlled by said magnet for enabling the last named abutment to be displaced, and a switch in circuit with said electromagnet for energizing the magnet. 125

4. A cable gripping and releasing means comprising a jaw adapted to bear on and bind a cable, a lever having an arm pressing on said jaw to hold the same against the 130

cable, and so arranged that the reaction of the jaw tends to shift it into an inoperative position, a dog holding said lever in the operative position, a detent preventing displacement of the dog, and means for displacing said detent and thereby permitting the dog to release the lever.

5. A cable gripping and releasing means comprising a jaw adapted to bear on and bind a cable, a lever having an arm pressing on said jaw to hold the same against the cable, and so arranged that the reaction of the jaw tends to shift it into an inoperative position, a dog having a toe against which a part of the lever bears holding said lever in the operative position, said dog being pivoted and having an arm, a detent obstructing said arm at a point more remote from its pivot than the toe preventing displacement of the dog, an electromagnet arranged to act when made active on said detent in such manner as will displace the same and thereby release said dog, and a switch in the circuit of said magnet for making the same active.

6. A cable gripping and releasing means comprising a jaw adapted to bear on and bind a cable, a lever having an arm pressing on said jaw to hold the same against the cable, and so arranged that the reaction of the jaw tends to shift it into an inoperative position, said lever having a second arm, a secondary lever pivoted to said second arm, an abutment on which one arm of said secondary lever rests, a dog on which another arm of the same lever bears, a detent obstructing movement of said dog under the pressure applied to it by said lever, and a controller for displacing said detent from its obstructing position.

7. A cable gripping and releasing means

comprising a jaw adapted to bear on and bind a cable, a lever having an arm pressing on said jaw to hold the same against the cable, and so arranged that the reaction of the jaw tends to shift it into an inoperative position, said lever having a second arm, a secondary lever pivoted to said second arm, a stationary abutment and a pivoted dog engaged with said said secondary lever at 50 points on different sides of the pivot thereof preventing movement thereof, the dog being movable out of the way of the secondary lever and having rolling contact therewith when so moving, a detent preventing such 55 movement of the dog, and means for disengaging said detent from the dog.

8. A cable gripping and releasing means for the purpose stated comprising a jaw adapted to bear upon and bind a cable, a pivoted lever having arms unequal in length of which the short arm bears against said jaw at an inclination to the reaction of the latter, a secondary lever against which the long arm of the first named lever bears, a stationary abutment and a pivoted dog supporting said secondary lever, a detent holding said dog against displacement under the thrust of the secondary lever, and an electromagnet arranged for shifting the detent into an inoperative position; the point of bearing of the first lever on the secondary lever being relatively near the abutment, and the point of contact of the secondary lever with the dog being more remote from the abutment; and said point of contact being nearer the pivot of the dog than the point of contact between the dog and the detent.

In testimony whereof I have affixed my so
signature.

JOSEPH F. WILSON.
